[57] **CLAIM**

The ornamental design of a shower head, substantially as shown.

DESCRIPTION

FIG. 1 is a side elevational view of a shower head showing my new design;

FIG. 2 is a bottom plan view thereof;

FIG. 3 is a top plan view thereon; and

FIG. 4 is an isometric view taken from the bottom thereof, showing the shower head in a position different from that shown in FIG. 1.

FIG. 1

FIG. 2

FIG. 3

FIG. 4
